UNITED STATES PATENT OFFICE.

JOHN M. BEIERMEISTER, OF TROY, NEW YORK, ASSIGNOR, BY MESNE ASSIGNMENTS, TO BEIERMEISTER BROS. COMPANY, OF NEW YORK, N. Y., A CORPORATION OF NEW YORK.

METHOD OF MAKING FOLD-COLLARS.

No. 806,815.

Specification of Letters Patent.

Patented Dec. 5, 1905.

Application filed February 5, 1904. Serial No. 192,136.

To all whom it may concern:

Be it known that I, JOHN M. BEIERMEISTER, a citizen of the United States, residing at Troy, county of Rensselaer, and State of New York, have invented certain new and useful Improvements in Methods of Making Fold-Collars, of which the following is a specification.

Reference may be had to the accompanying drawings and the reference characters marked thereon, which form a part of this specification.

Similar characters refer to similar parts in the several figures.

Figure 1 of the drawings is a plan view showing connected together by run-seams the various plies adapted to form my improved collar, except the facing for one of the projecting ends of the band, the continuous top and band ply being shown uppermost in said figure. Fig. 2 is a view of the same inverted from the position shown in Fig. 1 with the separate top and band plies uppermost. Fig. 3 is a cross-section of the same, taken on the broken line 3 3 in Fig. 1. Fig. 4 is a plan view of the facing for the projecting end of the band omitted from Fig. 1. Fig. 5 is a plan view of one end of the unfinished collar, showing the separate band ply drawn out into line with the continuous top and band ply and with the projecting end portion of the band turned inside out. Fig. 6 is a cross-section of the same, taken on the broken line 6 6 in Fig. 5. Fig. 7 is a view similar to Fig. 5, showing the collar top turned inside out and the free edge of the separate band ply inturned. Fig. 8 is a cross-section of the same, taken on the broken line 8 8 in Fig. 7. Fig. 9 is a cross-section taken on the broken line 9 9 in Fig. 1 of the projecting faced end of the band when the same is turned inside out. Fig. 10 is a cross-sectional view of the same on the broken line 10 10 in Fig. 5 after the same has been turned inside out. Fig. 11 is a plan view of the reversed side of the finished collar. Fig. 12 is a plan view of the obverse side of the same. Fig. 13 is a cross-section of the same on the broken line 13 13 in Figs. 11 and 12. Fig. 14 is a similar view, on an enlarged scale, showing the collar top folded over upon the band to the position assumed in use.

50 The principal object of my invention is to produce a fold-collar having on its obverse side a continuous top and band ply and on its

reverse side separate top and band plies of the usual dimensions.

In carrying out my invention I employ a 55 continuous top and band ply 1 of the usual length of a top ply and of a width equal to the combined widths of the usual top and band plies of a fold-collar. Secured to its continuous top and band ply along three of its edges 60 in inverted position by means of a run-seam 2 is a separate top ply 3 of usual width, the manner in which the same is secured being substantially the same, in which two plies of a collar top are secured together by a run-seam preparatory to being turned inside out by hand in the usual manner. Secured along the fourth edge of the continuous top and band ply in inverted position by means of a run-seam 4 is a separate band ply 5 of usual 70 width. Short facing plies 6 are secured in inverted position by continuations 7 of the run-seam 4 to the projecting ends of the separate band ply 5 in position to overlap slightly the respective corners of the continuous top 75 and band plies where the same are connected with the separate band ply 5, as shown at the left-hand end of Fig. 1, where the top plies are folded back for convenience of illustration and also to illustrate the manner in 80 which the top plies are withdrawn to permit the continuation of the run-seam 7 through the facing ply and separate band ply only. Previous to the application of the facing plies 85 6 the end of the continuous top and band ply adjacent to the corner where the same is connected with the separate band ply is folded back upon the side opposite that to which the separate top ply 3 is attached, as shown at 8 in Fig. 1, after which the facing ply 6 is superposed thereupon and secured by the extension 9 of the run-seam, which serves to securely unite the folded corner 8 of the top and band ply, the adjacent edge of the separate band ply, and said facing ply.

The manner in which the parts named are secured together by run-seams is shown in Figs. 1, 2, and 3. After being so secured together the separate band ply is drawn out into approximately the same plane with the continuous top and band ply, as shown in Figs. 5 and 6, and the projecting faced end of the band is turned inside out, as shown in Fig. 5. The separate top ply is then turned

inside out over upon the opposite side of the continuous top and band ply to the position shown in Figs. 7 and 8, and the free edge of the separate band ply is inturned, as shown 5 at 10 in said figures. The separate band ply is then folded over along the line of its run-seam connection 4 upon the band portion of the continuous top and band ply with its folded edge 10 applied to an overlapping and 10 unfinished edge 12 of the separate top ply 3, and a line of stitching 13 is inserted through the infolded edge 10 of the band ply and the other folds of the collar along the fold-line thereof. An edge line of stitching 14 is then 15 inserted along all the edges of the top and band and buttonholes are inserted in the usual manner to complete the collar.

A collar thus formed presents no seam along the fold-line on its obverse side, but is provided with such a seam along its fold-line on 20 its reverse side formed by a folded edge of the separate band ply, which serves as a guide in folding the top over upon the band of the collar in position for use.

25 What I claim as new, and desire to secure by Letters Patent, is—

The herein-described method of making fold-collars which consists in forming a con-

tinuous top and band ply equal to the combined widths of the usual separate top and band plies of a fold-collar, securing along three sides thereof a separate top ply with the connected edges inturned and concealed between said plies, securing along the fourth side of said continuous top and band ply in inverted position by a run-seam a separate band ply, inturning the ends of the band portion of the continuous top and band ply to form a folded edge thereon when finished, securing to the projecting ends of the separate 35 band ply a facing ply with their connected edges inturned and concealed, inverting the free edge of the separate band ply, folding over the separate band ply upon the reverse side of the band portion of the continuous top 40 and band ply with its folded edge lapping the unfinished edge of the separate top ply, securing the lapping edges of the separate top and band plies together by stitching, and finishing the collar in the usual manner. 45

In testimony whereof I have hereunto set my hand this 30th day of January, 1904.

JOHN M. BEIERMEISTER.
